(57) **CLAIM**

The ornamental design for a cover for electronic device, as shown and described.

DESCRIPTION

FIG. 1 is a front, top, and right-side perspective view of a cover for electronic device, showing our new design;

FIG. 2 is a front view thereof;

FIG. 3 is a back view thereof;

FIG. 4 is a right-side view thereof, the left-side view being a mirror image;

FIG. 5 is a top view thereof;

FIG. 6 is a bottom view thereof; and,

FIG. 7 is a rear, top, and right-side perspective view thereof.

The drawings are executed in grayscale. Grayscale shading illustrates contour and does not represent any particular color. The features shown in white in FIGS. 3 and 6 depict interior portions seen through openings of the cover for electronic device, and form no part of the claimed design.
